ABSTRACT: A heating platen press for manufacturing composition board, such as chipboard, shavings board, and the like. The press includes a stationary base unit and a movable press unit which respectively have working, heating platens directed toward each other and respectively provided with parallel working faces. These units are each composed of a box structure which includes, in addition to the heating platen, an opposed cover plate and longitudinal bracer bridges which extend between and engage the cover plate and heating platen. The heating platen and cover plate of each unit are formed with channels for conveying a temperature-controlling fluid therethrough, so that the entire unit can be heated and cooled. Each longitudinal bracer bridge has at least one row of such channels extending longitudinally through the bracer bridges.

HEATING PLATEN PRESS

My invention relates to heating platen presses of the single-opening or multiple-openings type.

Such presses are used for the manufacture of composition board, such as chipboard, flakeboard, shavings board, fiber board, and the like.

The heating platen presses conventionally include a fixed based and a movable press unit, each of these units forming a box structure which is capable of being heated and cooled in its entirety. Each box structure includes the heating platen, an opposed cover plate, and longitudinally extending bracer bridges and transverse ribs. The heating platen and cover plate of each box structure are formed with channels for conveying heating or cooling fluid therethrough.

Many known forms of such heating platen presses primarily include a frame which carries a stationary base and a movable press assembly. The cylinder pistons are conventionally situated either over or under the movable press assembly. The heating platens are situated between the fixed base and the movable press unit and in fact form part of the base and unit which have their heating platens directed toward each other.

A single-opening press has a single base and a single movable press assembly. On both sides of the installation there are cylinder-and-piston assemblies connected to the base through suitable columns.

Because of economic considerations in the manufacture of such presses and in order to avoid distortion of the base and movable press unit as result of the high heating temperatures, it has become customary in recent times to make the base and movable press unit themselves serve as the respective heating platens, the entire structure of the base and movable press units being heated or cooled.

Two constructions of such primary press components are known at the present time.

With one of these constructions the base and movable press units are each in the form of a welded assembly having a box structure provided with a cover plate strengthened by longitudinal bracer bridges so that the chambers between these bridges form ducts for the heating fluid. Where steam is used for heating purposes, a uniform temperature distribution at the surfaces of the cover plates is achieved. However, a great disadvantage of this construction resides in the fact that in order to achieve heating to a temperature of 250° C, the pressure in the interior steam chambers must be raised to approximately 25 atmospheres. For these reasons special safety measures must be taken, requiring official inspections at predetermined time intervals. A structure of this latter type is not suitable for heating with hot water and in particular with oil, because with the large interior chambers a heating medium of this latter type can provide a good heat transfer only under conditions of turbulent circulation.

With the second type of known construction the base and movable press units are also formed of welded structures. They include cover plates which are combined with longitudinal and transverse bracing members for strengthening purposes. The heating takes place in a conventional manner in that the cover plates are formed with simple rows of channels situated one next to the other in order to provide a path of flow for the heating fluid.

The cover plates of a coacting base and movable press unit are situated distant from and directed away from each other, and the temperatures of such upper and lower plates can be maintained equal to each other, or by way of differential heating a predetermined distortion of the base or movable press unit, and thus of the working faces of the platens can be provided. However, during heating up of the structure there occur detrimental tensions between the hot working platens and the bracer bridges.

Deformation resulting from the differential heating of such construction takes place both longitudinally and transversely. In this respect the edge and corner regions of the structure are at a particular disadvantage because of the additional radiation heat loss occurring at these localities.

A further disadvantage of both of the constructions of the above type resides in the fact that during the press operations a large output of heat is required in a rapid, shockwise manner. This results in considerable temperature differences in the base or movable press unit, particularly at the working faces thereof. Where the cover plates are formed with channels, these temperature differences occur because there is an insufficient amount of flow of the heating fluid, while with the box type of construction having large interior chambers, the lack of turbulence in the heating medium results in the large temperature differences.

It is thus a primary object of my invention to provide heating platen presses which avoid the above drawbacks.

In particular, it is an object of my invention to provide, for presses of this type, box structures forming base or movable press units and capable of being heated in their entirety.

Also, it is an object of my invention to provide a construction which will reliably produce pressure transmission between accurately parallel and accurately planar working faces of the heating platens of the base and movable press units by applying heat during the pressing operation.

In accordance with my invention, the heating platen of the base and movable press units is provided with at least a pair of rows of channels for the temperature-controlling fluid, with these channel rows being respectively situated in different planes with respect to the working face of the platen.

Also, in accordance with my invention the longitudinal bracer bridges are formed with one or more rows of channels for the temperature-controlling fluid.

It is also further object of my invention to provide a construction which can very rapidly compensate for heat losses so as to minimize stresses resulting from temperature differentials. Thus, in accordance with my invention, the temperature drop encountered during the pressing operations at the working faces of the platens is compensated by utilizing the counterflow principle with several systems of fluid channels which derive their heat from the capacity of a heat reservoir formed by the entire structure so as to direct this additional heat supply to the heating platens. Thus, at the beginning of the pressing operation, the temperature differential resulting from delivery of heat to the work material is rapidly equalized between the heating platen and the rest of the box structure, so that in the shortest possible time a uniform temperature prevails at all parts of the box structure.

In order to enhance this latter feature, there is provided in accordance with my invention an additional heating operation in a primary circuit which forms the main heating for the work faces of the heating platens.

The second row of channels of each platen, which is more distant from the working face thereof, forms a secondary circuit for the heating medium, and this secondary circuit also includes channels formed in the longitudinal bracing bridges and channels formed in one or two rows in the cover plate of each unit. However, in accordance with the particular size of the heating platen press, it is also possible to provide each box structure with one or more primary circuits and with one or more secondary circuits.

Each unit, which is to say a base unit or a movable press unit, defines a mechanically neutral plane situated midway between and extending parallel to the heating platen and cover plate, and the individual heating or cooling circuits are properly situated with respect to this neutral plane, so that each box structure will be for the most part free of any distortion throughout its entire construction.

It is of course important that the same temperature relationships prevail on both sides of the neutral plane. In particular, through the heating of the longitudinal bracer bridges it is possible to achieve a distortion-free influence on the entire box structure. By including regulating or mixing valves within the individual channel systems it is also possible to influence and control the extent of distortion of the press units.

With relatively lightweight presses, it is possible under certain circumstances to eliminate one of the rows of channels of the cover plate of each unit.

A particularly favorable type of heating of each box structure, whether it be the box structure of the base unit or the box structure of the press unit, is provided in the case where the row of channels of the heating platens are rapidly supplied by way of the primary circuit with more heat than the amount which is lost through the greater radiation and through the heat absorbed by the work material. This makes it possible that shortly before the end of the pressing operation the working faces of the platens have their initial planar parallel configurations.

A particularly effective heating of the platens and cover plates can be achieved by an arrangement of several rows of channels, if, in accordance with my invention, a pair of rows of channels are combined into a pair of heating loops in such way that the channels of one row alternate in a given circuit with the channels of the other row so as to be traversed by the mediums of both heating loops. This permits reducing the heating time and hence also the total time required for a pressing operation.

In order to provide a proper thermal expansion during heating of a platen box structure, it is above all of importance with short pressing times that the working face have a uniform temperature at all parts thereof. For this purpose, it may be necessary to additionally heat the four corners of such a box structure, or to intensify the extent to which the heat is retained at all sides of the base and movable press units, aside from the working faces.

Up to the present time it has been customary to control the temperature of the heating platens by way of surface contacts or thermocouples or other temperature-responsive elements situated in additional bores of the heating platen. Thus, the temperature values which form the basis for the control and regulation are those which are present in the material of the heating platen at the instant when a measurement is taken. Additional measurements can also be derived at other locations of the base or movable press unit.

These latter arrangements are of disadvantage, however, in that the temperature values derived from measuring the temperature of the solid material do not correspond precisely with the actual heat energy which has been delivered, since the heat spreads only sluggishly throughout the large masses until temperature compensation is achieved between the heated and the nonheated components of the base or movable press unit. Thus, the control by way of temperatures derived from the material of the press itself is much too slow and cannot provide accurate operations in the case where a press operating cycle lasts for only a few minutes, since the time required for the spreading of the temperature with accompanying temperature compensation in the base and movable press units is on the order of several hours.

Thus, according to a further feature of my invention, the heating of the box structure of each unit is controlled by measuring the temperature of the heating fluid where it leaves the heating platens in the primary or secondary circuits. By way of the temperatures measured at the discharge of the heating platen, it is possible to obtain precise information and exact values with respect to the amount of heat absorbed by the heating platen between the inlet and outlet of the circuit for the heating medium, so that these measurements can be used for an accurate control of the heating or cooling time, or the temperature difference between the inlet and outlet of the heating medium is a measure for the precise and very sensitive controls of the installation.

It is desirable in the industry to provide heating platen presses which achieve not only an improvement in quality of the product obtained but also a reduction in the time required for the pressing operations. The possibilities of conjointly meeting these requirements include enlarging the working faces of the heating platens, increasing the pressure, and increasing the heating temperature.

An increase in the size of the work faces of the heating platens by use of larger heating platens is available only within certain limits, since the required tolerances cannot be

achieved by planing or other machining operations. By increasing the pressure and heating temperature with the conventional presses, it is, on the other hand, no longer possible to reliably transmit the compressive forces with required tolerances from flat, parallel working faces to the work material.

In recognizing these latter considerations, a further feature of my invention resides in assembling the working faces of the heating platens of the stationary and movable units from a plurality of box structures according to the principle of assembly of prefabricated units. The individual box structures are built in the form of distortion-resistant units, particularly of large height, having proper thermal expansion. Several of these box structures are then assembled together at their wider sides in such a way that they form the length of a multiple-part base or movable press unit of a heating platen press. Particularly in combination with a heating platen press having tension columns provided with press cylinders at the long sides thereof, there is the possibility of effectively achieving a press with particularly large working faces at the platens and with low tolerances.

In order to make the box structure particularly resistant to bending, and in accordance with another feature of my invention, the respective stationary and movable press units are made up of a plurality of box structures. The cylinders and pistons are situated at the two long sides of the press, which is to say at the ends of a box structure. For this purpose the longitudinal bracing bridges are situated to the left and right of the width of the working face of the platen where they carry walls to receive the working cylinder-and-piston assemblies. While with a movable press unit which has a total of four longitudinal braces, only a pair of intermediate braces are required to carry the walls which coat with the cylinder-and-piston assemblies, all four of the longitudinal bracing bridges of the base unit box structure are required for the walls which coat with the cylinder-and-piston assemblies, so as to provide in this way a fixed support for the tensioned columns and a proper support for the pressure pistons. By way of these walls which are also reinforced by transverse ribs, in the same way as the platens, the pressure of the press is transmitted to the platens. Above and below, these walls are provided with pressure distributing plates which for the purpose of a better spreading of the pressure extend into cutouts of the longitudinal bracing bridges in the region of the press platens.

The transmission of a high specific pressure can be assured with a good resistance to bending by a relatively large inertia moment for the box structure. For that reason the ratio between the height of the bracing bridges with respect to the effective width of the working faces of the platens preferably is smaller than 1 : 1.8.

A further advantageous feature of my invention resides in the determination of the thickness of the work by way of spacer elements in the form of spacer plates of large area supported on spacer members which are mounted on the fixed, stationary unit. The spacer elements are situated with the spacer members at a location displaced from the operating region of the working faces where the walls of the movable press unit are provided to coat with the cylinder-and-piston assemblies. For each pressure piston there is a spacer plate of large area, and this area is determined by the width of the wall which coats with the hydraulic structure and the distance between a pair of tension columns.

With an advantageous arrangement of this latter type where the components are located along the piston axis a particularly favorable transmission of pressure from the movable press unit to the stationary base unit is achieved. The bearing supports for the press, equal in number to the number of pressure pistons, are also arranged along the piston axes, respectively.

The interconnection between the individual box structures can take place by way of bolt-and-nut assemblies. The bolts of these assemblies can pass through from one longitudinal bracer bridge to the next, and in this way through several box structures. The bolts or tie rods which thus pass through

several box structures can be tensioned with a suitable tensioning means in the form of cup springs while the tensioning means can also include end pressures derived from hydraulic cylinders. Such hydraulic cylinders afford an exact control of the pressure. It is also possible, however, to select for the cup springs a force which is so great that they will take up the entire pressure.

In order to assemble a plurality of box structures into a unitary assembly having a common planar working face for the platen, as well as in order to transmit the force from one box structure to the next box structure, there is provided in accordance with a further feature of my invention a five-wedge connection from one box structure to the next, this five-wedge means being preferably situated in the above-mentioned neutral plane of each box structure. This five-wedge means permits to adjust and hold the individual box structures with respect to each other so as to secure a common planar working face for the platen precisely within the required tolerances.

A further feature of my invention for assembling together several box structures to form a common press unit of long length, resides in situating the connection between a pair of box structures precisely midway between the cylinder-and-piston assemblies thereof.

If a box structure is manufactured from welded components, care is taken with respect to this latter measurement to guarantee that during heating and cooling stresses while the press is operating, no deforming action will take place at the working faces of the platens. Thus, the long welding seams can during welding result in heat stresses which bring about a distortion of the box structure, which distortion cannot be eliminated completely by annealing.

By a suitable arrangement of openings and cutouts in the longitudinal bracer bridges and the transverse ribs, with respect to the neutral plane, the box structure can expand and contract correspondingly when encountering thermal stresses, without reaching an excessive stress peak. In the longitudinal bracing bridges there are preferably a pair of openings of such great size that they will also serve as operating openings for entry and exit of the operator.

The invention is illustrated by way of example in the accompanying drawings which form part of this application and in which:

FIGS. 1-7 schematically illustrate various heating possibilities for a box structure according to my invention;

FIGS. 8-19 schematically illustrate various heating possibilities for heating platens having two or three rows of channels forming two or three heating loops;

FIGS. 20a, 20b, 20c and 20d are schematic illustrations of the use of a box structure of my invention in relatively light installations as a loose heating platen for multiple daylight presses;

FIG. 21 is a schematic side elevation of a heating platen press;

FIG. 22 shows the press of FIG. 21 as it appears from the side, FIG. 22 being partly in section;

FIG. 23 is a plan view of a stationary base unit of the heating platen press, taken along line C-D of FIG. 22;

FIGS. 24-29 show constructive details of a box structure of my invention in plan, elevation, and side views;

FIGS. 30a, 30b and 30c show various embodiments of transverse ribs;

FIG. 31 is a partly sectional schematic elevation showing the connection between a pair of box structures by means of bolt-and-nut assemblies and the five-wedge means of my invention;

FIGS. 32-35 illustrate details of the five-wedge connection; and

FIGS. 36-38 show the connection between a plurality of box structures by means of tie rods.

The box structures schematically illustrated in FIGS. 1-7 illustrate the heating possibilities for the closure plates 1 and 2 of the box structures which act as heating plates, particularly

with box structures where the top and bottom plates have two rows of channels while the longitudinal bracer bridges 3 are also formed with channels passing therethrough. For each of the units shown in FIGS. 1-7 there are transverse ribs 4 and a working face 5 forming the flat, planar face of the heating platen 1. The type of heating described in connection with FIGS. 1-7 is applicable not only to a movable press assembly but also to a stationary base unit.

In accordance with my invention, the first row of channels 6, which is in a plane nearest to the working face 5 of the heating platen 1, is in the form of a series of bores respectively having their axes situated in a common plane parallel to the plane of the working face 5, these bores of the first row forming a primary circuit to provide the operating heat. The second row of channels 7 is also in the form of a series of bores having their axes respectively situated in a common plane parallel to the face 5. The first row of channels 8 of the cover plate 2 as well as the second row of channels 9 of the cover plate for those embodiments where the coverplate has two rows, form with the channels 10 of the bracer bridges 3 one or more secondary circuits which during the pressing operations give up the stored heat on the counterflow principle to the primary circuit or to the heating zone where the primary circuit is located. These secondary circuits also serve to equalize temperature differences within the box structure.

A circuit is to be understood as comprising a closed conduit system where the heating medium at a predetermined temperature is directed through the closed system from a heat exchanger by way of a circulating pump. The system may comprise regulating and mixing valves. The heating medium is recirculated back to the heat exchanger through the channels which are to be heated, one or more passes connected in parallel or in series being provided for the heating fluid.

According to FIGS. 1, 2 and 4, the heating medium of the primary circuit is conveyed from the heat conduit 11 through the heat conduit 17 into and along the first row of channels 6 and then from the latter through the discharge conduit 22 to the return flow conduit 14. In FIGS. 3, 5, 6 and 7, the discharge conduit 22 is followed by a connection to the first row of channels 8 of the cover plate 2, the row of channels 8 being connected in series. The first secondary circuit is preferably always directed in counterflow with respect to the primary circuit by way of the heating conduit 12, the heat conduit 18 and the discharge conduit 23 which coact with the second row of channels 7 of the heating platen 1. The heating fluid is also supplied by way of a parallel connection through the feed and discharge conduits 20 and 25 to the channels 10 of the bracer bridges 3, these channels being symmetrically arranged on both sides of the neutral plane A-B which extends parallel to and is situated midway between the heating platen 1 and cover plate 2. In the case where there is no additional secondary circuit, the first secondary circuit will supply either in parallel or in series also the first row of channels 8 of the cover plate 2 or the second row of channels 9 thereof, where such a second row is present, and also the channels 10 of the bridges 3 will be supplied at both sides of the neutral plane A-B.

For a particularly accurate control of the temperature relationships in the box structure, a second secondary circuit is provided in such a way that it acts either as a temperature compensation or equalizer for the primary and first secondary circuit. According to FIG. 2 the second secondary circuit feeds the single row of channels 8 of the cover plate 2, and parallel thereto also the channels 10 of the bridges 3 beneath the neutral plane A-B. In FIG. 4 the second secondary circuit feeds only the first row 8 of channels of a two-row cover plate 2. In FIG. 6 the second secondary circuit comprises the second channel row 9 of the cover plate 2' and, parallel thereto, the bracer bridge channels 10 beneath the neutral plane. These heating loops are connected by feed conduits 19, 21 to the heat conduit 13 and by discharge conduits 24, 26 to the return conduit 16 of the second secondary circuit.

According to FIG. 5, the channel rows 6 and 7 of the platen 1 are series connected in the primary circuit. The first secondary circuit extends through the parallel-connected bracer bridge channels 10 in two heating loops. The two channel rows 8 and 9 of the cover plate 2' are series connected in the second secondary circuit.

In FIG. 7 the first channel rows 6 and 8 of platen 1 and cover plate 2' respectively are series connected in the primary circuit; the respective second rows 7 and 9 are series connected in the secondary circuit operating in counter flow to the primary circuit. The channels 10 of the bridges 3 are connected in two heating loops parallel to the secondary circuit.

However, in certain cases a plurality of different types of heating arrangements can be used in the case where the stationary base or movable press units are each composed of a plurality of box structures. For example, the heating platens arranged at the edge of the box structure can be heated by concurrent flow of the primary and secondary circuits. With such an arrangement, the inlet and discharge regions of the primary circuit and the first secondary circuit are situated at the edge regions one over the other. Thus, the edge regions, such as, for example, the left side of the first box structure and the right side of the last box structure can be supplied with a greater amount of heat, so that it is possible to compensate in this way for the greater radiation at the edge regions.

The advantageous arrangement of two or more rows of channels in the heating platen of the box structure can be further improved if, according to FIGS. 8-19, a pair of rows of channels are interconnected to form a pair of counterflow heating loops in such a way that the loops alternately include channels of the first and second rows.

According to this feature of my invention, it is possible to quickly and uniformly heat the heating platen as well as to achieve for predetermined cross sections an over or underheating. An overheating of an edge section can be achieved, for example, by providing for the first two or three channels of the first and second rows of channels heating loops located directly beside each other, which is to say without situating a channel of the second heating loop in-between. Thus, such an edge section will initially have the highest temperature fluid flowing therethrough.

The second heating loops are preferably supplied from a heating conduit. It is, however, also possible, in particular where one of the two heating loops has its entrance at the front side and the other has its entrance at the rear side, to provide a pair of heating channels. FIGS. 8-19 schematically illustrate the preferred interconnection of the channels of two or three rows of channels of a heating platen or cover plate under particular operating conditions to meet particular requirements.

The entrance into a heating loop is indicated by an arrow directed toward the center of the inlet channel, while an arrow from the center of the outlet channel illustrates the discharge path for the heating fluid. Whether the inlet or outlet is situated at the front side or back side of the heating platen can be recognized from the fact that an arrow at the front side is situated beneath the channel while an arrow at the rear side is situated over the channel. The connections of the individual channels are situated at the front side where solid interconnecting lines are shown and at the rear side where broken interconnecting lines are shown, with the structure being arranged in such a way that the connection between the channels is situated within the platen.

Further possibilities are to interconnect individual channels by way of curved tubes at the exterior of the platen.

The simplest connection of a pair of rows of channels by way of heating loops I-II and II-II is illustrated in FIG. 8. With this arrangement the entrances for the pair of heating loops will be situated at the front side and the discharges thereof at the rear side.

The first heating loop I-I has its entrance in the first channel of the first row, which, for example, is situated nearest to the working face of the platen, while the second heating loop II-II

begins at the first channel of the second row of channels. This arrangement is applicable to an odd number of channels in the first and second rows of channels.

Assuming that there is an even number of channels for the rows of channels, as illustrated in FIG. 9, then the entrance for both heating loops is situated in the first row of channels, which is of advantage for a better supply of heat to the first row of channels but requires at the front as well as the rear side of the heating platen a heating conduit and a return flow conduit.

With the same arrangement it is possible to fulfill an other requirement, as shown in FIG. 10, namely that the left edge region be supplied with a greater amount of heat inasmuch as an odd number of channels of the rows of channels, counted vertically and in pairs, are interconnected in such a way that the first two channels situated one above the other are combined into a single heating loop. One of the heating loops of this arrangement, therefore, has two channels more than the other heating loop. In a corresponding reversal of the heating loops it is possible also to supply a greater amount of heat to the right side. The same is true of an even number of channels, also counted in pairs, as shown in FIG. 11 where the remainder of the arrangement corresponds to that of FIG. 8.

The arrangement of FIG. 12 fulfills the requirement of situating both entrances at the front side and both discharges at the rear side while at the same time supplying more heat to both edge sections.

The arrangements of FIGS. 13-17 show embodiments in which the entrance and discharge regions of both heating loops are situated on one side, while in all cases one or both edge regions are supplied with a greater amount of heat. A further feature is present in FIGS. 15-17 in that both heating loops start in the first channels of the first row.

FIG. 18 shows a further variation of the interconnection between the channels of a pair of heating loops. In this case both heating loops start in the first channels of the first row but not at the same side. The discharges are located also one at the front and one at the rear.

FIG. 19 shows the possibility of interconnecting three rows of channels of a heating platen into three heating loops. Under certain circumstances it may be of advantage to use the third row of channels in a secondary circuit and the first two rows of channels are interconnected as indicated in FIGS. 8-18.

Although the above description refers to heating the different arrangements, the same considerations apply to cooling.

FIGS. 20a, 20b, 20c and 20d schematically and fragmentarily illustrate in a sectional elevation an arrangement having two press boxes 28 of my invention in the form of relatively light structures acting as loose heating platens for multidaylight presses. The box structures are reinforced by longitudinal bracer bridges and transverse ribs which form webs between the bracer bridges. The heating platens have at least two channel rows arranged in respectively different planes parallel to the platen face. The longitudinal bracer bridges also have one or more parallel rows of channels. These loose, light heating platens coat with two heavier, fixed and movable press units 27 so that the relatively large amount of heat present in the loose heating platens serves to reduce the time required for a press operation.

FIGS. 21-29 show the heating platen press as well as the box structures 29 and 30 according to my invention in their constructive details. The press consists primarily of the stationary fixed base units and the movable press units, these movable press units being made up of a plurality of box structures 29 shown more precisely in FIGS. 24-26 while the stationary base units are made up of a plurality of box structures 30 shown more accurately and in greater detail in FIGS. 27-29.

The movable press unit is supported by way of a return stroke assembly 48 on the cylinder-and-piston assembly of the press, this assembly being made up of the pressure piston 35, the tension columns 38, and the press cylinders 43. The fixed

base unit rests on the supports 42 which are situated along the axes of the press pistons 35. At the region of the press faces the longitudinal bracer bridges 45, 46 and 47 carry the platens in the form of a heating or press platen 31 and a cover plate 32 each formed with a pair of rows of heating channels.

While in a case of the movable box structures 29 the pair of intermediate bridges 46 are extended to form right and left walls 33 for connection with the cylinder-and-piston assemblies, the box structures 30 of the base units have all four bracer bridges 47 extended beyond the region of the working faces to the left and right to form the additional walls 34 which also serve as guides for the tension columns 38. In order to strengthen the box structures 29 and 30 and the walls 33 and 34 in the transverse direction, transverse ribs 44 are provided.

Spacer members 40 are carried by the walls 34, and these spacer members 40 coat with the walls 33 of the movable box structures 30, these walls 33 being offset with respect to the press region, by way of spacer plates 39 of large area. On the walls 33 and 34 there are lower and upper pressure distributing plates 36, 37, 40 and 41 arranged in such a way that they extend partly into the region of the press platen. In order to coat with the spacer plate 39 the pressure distributing plates 37 of the walls 33 are provided with protective plates 61 (FIG. 24). The area of members 40 and spacer plates 39 preferably has a length corresponding to the free spacing between the tension columns 38, and a width corresponding to the distance from the longitudinal edge of the platen 1 to the edge of the box structure. In any event, the spacer plates 39 should have an area at least equal to that of the pressure plunger 35. As also shown, the plates 40 and the spacer members 39 preferably extend straight along the geometric axis of the plunger.

With particularly heavy and large heating platen presses, openings are required in the bridges 45, 46 and 47 for the assembly of the components as well as for compensation for thermal expansion during operation, so that only relatively few heating channels 60 can be provided, as indicated in FIG. 26. In the box structures 29 and 30 or in their bridges 45 and 47 the adjustment and holding of the units in predetermined positions with respect to each other are brought about by way of a five-wedge means situated in recesses 59 centrally arranged with respect to the neutral plane A-B.

For compensating for thermal expansion during heating and for contraction during cooling of the press, as well as for welding the components of the box structures 29 and 30 together without machining or cutting operations, thermal expansion openings are provided on both sides of the neutral plane A-B in the bridges 45, 46 and 47, and particularly in the transverse ribs 44. The longitudinal bridges 45, 46 and 47 preferably have each a pair of large operating openings 49, eight channels 50 for each bridge, these bores or channels 50 also serving to accommodate the bolt-and-nut assemblies 62, 63 or the tie rod connecting units 66, so that in this way two or more box structures 29 or 30 can be assembled together, the bridges also being each provided with four tension interrupting cutouts 51 at the location of the long welding seams.

As may be seen from FIGS. 30a, 30b and 30c, the transverse ribs 44 may be made in three different ways, in accordance with my invention. In all three embodiments the four corners of the rectangular transverse ribs are provided with cutouts 53. At their central regions, the transverse ribs 44 can be provided either with thermal expansion slots 54 and 55 or with a pair of elongated cutouts 58 symmetrically situated with respect to the neutral plane A-B. Where the slots 54 are enlarged at their ends by way of bores 55, it is sufficient to situate at both sides a pair of stress-interrupting cutouts 56, while in the case of FIG. 30b where the rod 57 is provided, each side edge is provided with a pair of stress-interrupting cutouts 56.

The connection of the pair of box structures 30 from one longitudinal bracer bridge 47 to the next by way of the bolt-and-nut assemblies 62, 63 is illustrated in FIG. 31. In FIGS. 32-35 the construction and manner of operation of the five-wedge connecting means of my invention is shown in section

for a pair of bridges 47 having the five-wedge means accommodated in their recesses 59. By proper pressing or hammering of the four wedges 65, or pressing them out of the recesses, it is possible to situate the bridges 47 at the proper elevation so as to achieve a common working face which is flat and plane. In this way manufacturing tolerances can be compensated. The large intermediate wedge member 64 serves only as a stabilizer for the four wedge members 65. After properly positioning the box structure 29 or 30, the parts of the wedge members which extend beyond the assembly are simply removed.

The interconnection of a plurality of box structures 30 by a tie rod 66 passing through the entire assembly is illustrated in FIGS. 36-38. By four strong cup springs 67 or several small cup springs 71, the box structures 29 or 30 can be held together properly by a tie rod 66 and nut 68 as shown in FIG. 36, or they can be prestressed and held together by a threaded nut as shown in FIGS. 37 and 38.

At the right end region of FIGS. 37 and 38 the connection includes a cylinder 69 and piston 72 which acts on the tie rod 66 through a strap 70.

The above-described individual box structures 29 and 30 are provided particularly for heavy presses with extremely large work faces and large operating pressures. However, even for relatively small heating platen presses operating with smaller work areas the box structure of my invention can be used with advantage.

However, with relatively small presses, the work faces of the stationary base and movable press units can be made up from a single box structure with, for example, a single platen and cover plate, having a length which extends over three pairs of cylinder-and-piston assemblies and made up of 10 longitudinal bracing bridges.

The advantages which can be achieved with a heating platen press according to my invention reside in the fact that with the platen and cover plate structures of my invention, provided with several rows of channels for the temperature-controlling fluid as well as with the inclusion of the longitudinal braces in the heating system, it is possible to have available a large reservoir of heat for the pressing operations.

An even greater advantage resides in particular in the fact that as results of the channels provided in the braces an additional heating up is possible. In this way the temperature can be precisely regulated on both sides of the neutral plane A-B and an almost stress-free heating up and cooling off of the press can be achieved.

Furthermore, the time required for the press operations can be reduced and by way of the many different types of heating possibilities and exact controls of the heating a guarantee of precise transmission for flat planar working faces can be achieved so that the quality of the work is enhanced.

It is furthermore of advantage that the constructive details of the press elements and their proper static, thermal and operating characteristics achieved with the structure of my invention guarantee also, even with extremely large working faces and high pressures, a perfectly flat, planar working face to transmit the pressure in a very precise manner. Also, because of the large area of the spacer plates which are arranged along the piston axes with the other components which transmit the pressure, a particularly good resistance to distortion of the box structures and thus of the entire press is achieved.

A further advantage of the heating platen press of my invention results from the fact that the design of the longitudinal braces and transverse ribs for proper thermal expansion with respect to the neutral plane eliminates any thermal stresses which could result in deformation of the entire structure of the press assembly. With this construction of my invention the thermal influences are active with respect to the neutral plane in such a way that preliminary or subsequent expansion or contraction can take place without transmitting the thermal stresses to the other components.

An advantage of my invention also resides in the fact that the structural arrangement of the individual components of my invention facilitates attaining box structures of any desired magnitude with welded assemblies.

I claim:

1. In a heating platen press for manufacturing composition board, a stationary base unit and a movable press unit respectively having heating platens with respective parallel working faces opposite each other, said units each being composed of a box structure including, in addition to said heating platen, an opposed cover plate and longitudinal bracer bridges extending between and engaging said cover plate and said heating platen, said heating platen and cover plate and said longitudinal bracer bridges of each unit being formed with channels for conveying a temperature-controlling fluid therethrough, so that the entire unit can be heated and cooled, at least one row of said channels extending longitudinally through said bracer bridges.

2. The combination of claim 1, wherein at least two rows of said channels are situated in respective planes parallel to and differently spaced from said working face of said platen.

3. The combination of claim 1 wherein both the heating platen and the cover plate of each unit are provided with at least two rows of said channels situated in different respective planes parallel to said working face of each unit.

4. The combination of claim 3 wherein channels of said cover plate and bracer bridges together with said channels of said platen form at least one heating-fluid circuit, said circuit forming a heat reservoir of the entire mass of the box structure of each unit so that the heat of said reservoir is available for the press operations, and each platen forming a heating zone in which the channels thereof are connected into said circuit for counterflow of the fluid so as to pass the stored heat from said reservoir to said heating zone.

5. The combination of claim 4 wherein each platen has the channels in the row nearest to said working face thereof forming a primary fluid-flow circuit, a secondary circuit means, the channels of the other row of each platen together with the channels of said cover plate being parallel connected in said secondary circuit means, said channels of said bracer bridges forming two fluid-flow loops parallel connected in said secondary circuit means.

6. In the combination of claim 5, each unit defining a neutral plane situated midway between and extending parallel to the platen and cover plate thereof, said channels of said longitudinal bracer bridges being situated on both sides of said neutral plane, said row of channels of said heating platen of each unit nearest to said working face thereof forming said primary circuit, said secondary circuit means comprising a first and a second secondary circuit, said first secondary circuit including the other row of channels of said heating platen together with the channels of said bracer bridges on the same side of said neutral plane as said heating platen, said second secondary circuit including the channels of said cover plate and the channels of said bracer bridges on the same side of said neutral plane as said cover plate.

7. The combination of claim 5 wherein the row of channels of said heating platen nearest to said working face thereof are connected in series with the row of channels of said cover plate in said primary circuit, the other row of channels of said heating platen of each unit forming part of said secondary circuit means which has individual heating loops including respective channels of said longitudinal bracer bridges.

8. The combination of claim 7 wherein the row of channels of the heating platen of each unit closest to said working face of said platen forms part of said primary circuit, the second row of each heating platen together with said bracer bridge channels on the same side of said neutral plane forming a first heating loop, said covering plate having a second row of channels connected in parallel with said heating loop, a second heating loop comprising the bracer bridge channels on the other side of said neutral plane and forming therewith a first secondary circuit, the other row of channels of said cover plate forming a second secondary circuit.

9. In the combination of claim 1, each unit defining midway between its heating platen and cover plate a neutral plane parallel to said heating platen and cover plate, said rows of channels of said platen forming a primary circuit, said cover plate of each unit having a pair of rows of channels which form a secondary circuit, said longitudinal bracer bridge channels being located above and below respectively said neutral plane, a secondary circuit having respective heating loops parallel connected with said bracer bridge channels above and below said plane respectively.

10. In the combination of claim 3, each unit defining a neutral plane situated midway between and extending parallel to the heating platen and cover plate thereof, said longitudinal bracer bridge channels being situated on both sides of said neutral plane, the row of channels of said platen nearest to said working face thereof forming part of said primary circuit, a first secondary circuit, the other row of channels of said platen together with the bridge channels on the same side of said neutral plane as said platen forming a heating loop of said first secondary circuit, a second secondary circuit, said cover plate of each unit having a row of channels connected with the channels of said bridges on the same side of said neutral plane as said cover plate to form a heating loop of said second secondary circuit.

11. In the combination of claim 1, each unit defining a neutral plane situated midway between and extending parallel to the heating platen and cover plate of each unit, said cover plate having a pair of rows of said channels respectively situated in planes located at different distances from the working face of said platen, said bracer bridge channels being situated on both sides respectively of said neutral plane, a primary circuit, the row of channels of said platen nearest said working face thereof together with one of the rows of channels of said cover plate being connected in said primary circuit, a secondary circuit, the other rows of channels of said platen and cover plate being connected in said secondary circuit, and said bracer bridge channels on opposite sides of said neutral plane being situated in respective two heating loops which are parallel connected with said secondary circuit.

12. The combination of claim 1 wherein the rows of channels of said platen form a pair of heating loops which start at side edges of the platen and which alternately include channels of both rows.

13. The combination of claim 1 wherein said interconnected rows of channels form a primary circuit, the cover plate of each unit also being formed with a pair of rows of channels interconnected in the same way as the channels of said platen of each unit and forming a secondary circuit.

14. The combination of claim 13 wherein said channels form a pair of heating loops for supplying to at least one edge region of each heating platen a greater amount of heat than to the remainder of the platen.

15. The combination of claim 1 wherein the channels of each heating platen form a fluid circuit having outlets, and means responsive to the temperature of the fluid at said outlets for controlling the temperature of each unit.

16. The combination of claim 1 wherein said channels form part of primary and secondary heating circuits, and said primary heating circuit having an amount of heat greater than that of said secondary circuit by the extent to which heat is lost from the heating platen by radiation and withdrawal of heat to the material being worked.

17. The combination of claim 16 comprising means for additionally heating the four corners of said heating platen for reducing heat losses at said corners.

18. A heating platen press for manufacturing composition board, a stationary base unit and a movable press unit respectively having heating platens with respectively parallel working faces opposite each other, each of said units being composed of a plurality of box structures, each box structure including, in addition to said heating platen, an opposed cover plate and longitudinal bracer bridges extending between and engaging said cover plate and said heating platen, said heating plate and cover plate of each unit having at least two rows of

channels for temperature-controlling fluid, said channel rows being differently spaced from said working face, said plurality of box structures being arranged in a row with all of said longitudinal bracer bridges parallel to each other and situated one after the other along said latter row from one box structure to the next, a pair of cylinder-and-piston assemblies coacting with each of said movable press units respectively, and a plurality of fastening means passing through said bracer bridges and rigidly securing a plurality of said box structures together into an assembly forming one of said units.

19. The combination of claim 18, comprising wedge means between and coactive with each pair of successive box structures of each unit for adjusting the box structures so that the working faces of the platens are in a common plane and for transmitting forces between the adjoining box structures.

20. The combination of claim 18, comprising spacer plates of large area for determining the thickness of the work material, spacer members which carry said spacer plates and have the same area size as said plates, said spacer members being situated beyond the pressing region of the platens, working pistons operatively connected with each movable press unit for displacing the latter, and said spacer plates respectively having center points situated in planes perpendicular to the axis of said piston.

21. The combination of claim 20 wherein one of said spacer members is provided for each of said cylinder-and-piston units respectively and is carried by the stationary box structures of the stationary base unit.

22. The combination of claim 20 comprising a pair of tension columns operatively connected with each movable press unit, the surface area of each spacer plate and spacer member having a length corresponding to the distance between said columns, said surface area being at least as great as the area of the pressing surface of said working piston.

23. The combination of claim 20 wherein pressure-distributing plates are situated between and operatively connected with each movable and stationary unit for transmitting the pressure therebetween, said distributing plates respectively being situated along the axes of said pistons which act on the movable unit whereby the pressure is transmitted through said pressure-distributing plates from said movable unit to said stationary unit, and said distributing plates carrying protective plates situated in line with said spacer plates and spacer members.

24. The combination of claim 1 wherein the ratio between the height of each of said longitudinal bracer bridges of a box structure with respect to the width of the effective working face thereof is smaller than 1:1.8.

25. The combination of claim 24 wherein each of said longitudinal bracer bridges is formed with an operating opening as well as with thermal expansion openings, each box structure having a neutral plane extending parallel to and situated between said platen and cover plate thereof, and said thermal expansion openings being situated on both sides of said neutral plane.

26. The combination of claim 25 wherein each box structure includes transverse ribs of rectangular configuration formed with cutouts at the four corners thereof and having thermal expansion openings on both sides of said neutral plane.

27. The combination of claim 26 wherein a press unit includes only a single box structure having more than four of said longitudinal bracer bridges and corresponding transverse ribs and having walls operatively connected with more than two cylinder-and-piston assemblies for providing the pressing force.
